UNITED STATES PATENT OFFICE.

JAMES W. LINDSAY, OF COHOES, NEW YORK.

JOINTER-GAGE.

No. 830,603.

Specification of Letters Patent.

Patented Sept. 11, 1906.

Application filed April 20, 1906. Serial No. 312,812.

To all whom it may concern:

Be it known that I, JAMES W. LINDSAY, a citizen of the United States, residing at Cohoes, county of Albany, and State of New York, have invented certain new and useful

Improvements in Jointer-Gages, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a view in isometrical perspective of a jointing-machine or planer provided with my improved gage. Fig. 2 is a side elevation, partly in section, of the gage detached. Fig. 3 is a top plan view of the same. Fig. 4 is a front elevation of the same.

My invention relates to attachments for jointing-machines or planers for finishing and truing the surfaces of boards for joiners' use.

The principal object of the invention is to facilitate the work of the operator and to adapt the machine for a wider range of use and for greater accuracy of work.

Referring to the drawings, wherein the invention is shown in its preferred form, 1 represents an ordinary wood-planing machine, 35 commonly known as a "jointing-machine," having the horizontal beds 2 and 3 on opposite sides of the rotary cutter 4, adapted to plane or smooth off the under side of a board which is moved along from the bed 3 to the bed 2 by 40 the operator. The beds 2 and 3 are adapted to be raised and lowered in the usual manner, the raising and lowering mechanism not being shown in the drawings.

Attached to the side of the machine about 45 opposite the end of the rotary cutter is a bracket 5, secured by means of bolts 6, inserted through apertures 7 in said bracket. Rotatively mounted upon said bracket is a socket-piece 8, containing a slideway for the 50 spindle 9, adjustable to different heights in said slideway by means of the screw 10, upon the upper end of which the lower end of said spindle rests. The spindle is secured in its slideway-socket against both rotative move-

ment therein and withdrawal longitudinally 55 therefrom by means of a set-screw 11, inserted through the wall of the socket into engagement with a recessed portion 12 of the spindle.

The socket-piece 8 is mounted upon the 60 bracket by means of a pivotal connection, the axis of which extends parallel with the side of the planer, said connection being formed by a cylindrical boss on one of said members adapted to fit into a similarly- 65 formed recess in the other, the parts being held together by means of a set-screw 13, as shown in Fig. 2.

Mounted upon the upper end of the spindle 9 is a head 14, to which is adjustably secured 70 the gage-arm 15, which overhangs the bed portion of the planing-machine directly above the rotary cutter thereof. The gage-arm is mounted upon the head 14 of the spindle by means of a pair of bolts 16, passing 75 through slotted apertures 17 in the arm into the head 14 of the spindle, said adjustment permitting the gage-arm to be located directly above the rotary cutter in all cases, it being impossible to attach the bracket 5 to 80 some machines in such a position as to properly locate the arm above the cutter in the absence of provision for adjustment of the gage-arm. The gage-arm is provided with a friction-roller 19, extending longitudinally 85 thereof, which roller in use is in substantially the same vertical plane with the rotary cutter.

My improved gage is adapted for various uses in connection with the planing-machine. 90 When used to reduce a board to uniform thickness, the board is first run through the planer to smooth one of its sides, after which the board is reversed to bring its opposite side in engagement with the rotary cutter 95 and is again run through the machine with the gage adjusted at the proper height to leave the board of the desired thickness. As the board is passing through the machine it is held by the operator up against the friction- 100 roller of the gage, so that the superfluous thickness of the board is removed from its under side by engagement with the cutter. For the purpose just described the gage-arm is maintained in a horizontal position, the 105 spindle 9 and the socket therefor being in vertical position, and in adapting the machine to work of different thicknesses the

height of the gage-arm can be varied from time to time as desired by loosening the set-screw 11, accomplishing the desired adjustment by means of the adjusting-screw 10, and 5 again tightening the set-screw 11.

Should it be desired to reduce the board to tapered or wedge-shape form in cross-section, one side of the board is smoothed or planed, as above described, after which the gage-arm 10 is adjusted at the desired angle by rotation of the socket-piece 8 upon the bracket, which rotation is permitted by loosening the set-screw 13, after which the parts are locked in 15 adjusted position by again tightening said set-screw. The arm is adjusted at the desired height in the manner above described and the inverted board is again passed through the machine, the operator holding its previously-planed surface against the arm of the gage. 20 The superfluous thickness of the board will thus be removed from its under side, which will occupy the horizontal plane of the bed of the machine, while the upper side will occupy an inclined plane corresponding with the 25 inclination of the gage.

In Fig. 4 the position of the gage for the use last described is indicated by dotted lines, the dotted line 18 indicating the plane of the bed of the machine, or the cutting-plane of 30 the knives. The gage-arm being supported in a position to extend across the bed of the machine directly over the rotary cutter also serves as a guard for the cutter, preventing

accidental contact therewith of external objects.

In inserting a board into the machine adjusted to materially reduce its thickness, the board is held in a tipped-up position with its upper forward corner beneath the gage and is then gradually lowered, forcing its lower forward corner against the cutter until the surplus material is removed from the under front side of the board, after which it is only necessary to guide the board by hand, pressing it upwardly with slight force against 45 the gage-roller. If desired, the bed 3 can be lowered to permit the insertion of the board and then gradually raised to proper position.

What I claim as new, and desire to secure by Letters Patent, is—

In a jointer-gage, the combination with a socket-piece provided with a spindle-slide-way; a spindle adjustable in said slideway; a screw for adjusting said spindle; and means for locking said spindle in adjusted position; 55 of a gage-arm projecting from said spindle at right angles thereto; and an attaching-bracket pivotally connected with said socket-piece on an axis extending at right angles to said spindle and said gage-arm.

In testimony whereof I have hereunto set my hand this 10th day of April, 1906.

JAMES W. LINDSAY.
